CLAIM

The ornamental design for a diagnostic test kit, as shown and described.

DESCRIPTION

FIG. 1 is an isometric view of a diagnostic test kit showing our new design;

FIG. 2 is a top plan view of the diagnostic test kit;

FIG. 3 is a right side elevational view of the diagnostic test kit;

FIG. 4 is a rear elevational view of the diagnostic test kit;

FIG. 5 is a bottom plan view of the diagnostic test kit;

FIG. 6 is an exploded isometric view of the diagnostic test kit, with its cover removed;

FIG. 7 is a top plan view of the diagnostic test kit without its cover;

FIG. 8 is an exploded isometric view of the diagnostic test kit without its cover, with its utensils removed; and

FIG. 9 is a top plan view of the diagnostic test kit without its cover or utensils.
